FLOYD D. BRYAN AND JOHN BLAUNER, OF ST. LOUIS, MISSOURI, ASSIGNEES TO S. G. ADAMS COMPANY, OF ST. LOUIS, MISSOURI, A CORPORATION OF MISSOURI

TRAFFIC SIGN OR SIGNAL

Application filed June 18, 1931. Serial No. 545,250.

This invention relates generally to traffic signs and has more particular reference to a traffic sign or signal of the self-reflecting type.

5 A traffic sign or signal of the self-reflecting type commonly comprises, so far as we are aware, a display-panel supported at the required elevation on a post or standard set in the ground, the panel carrying a plurality of light-reflecting indicia suitably arranged for traffic-warning purposes and the like.

Further, so far as we are aware, as the panel of the sign is generally constructed 15 merely of sheet-metal, the manner of supporting the panel must take into account the inherent weaknesses of sheet metal structures. At the same time, consideration must be given to the frequent necessity of replacing or replacing the light-reflecting 20 elements in the panel for maintaining the efficiency of the sign in its intended functions.

Our invention has hence for its chief object 25 the provision of a traffic signal or sign embodying unique means for mounting the sign-panel on its supporting post in a manner adequately enabling the sign to safely withstand the stresses to which in service it 30 may be subjected and permitting ready and convenient access to the reflecting elements for maintaining the service or signalling efficiency of the sign.

And with the above and other objects in 35 view, our invention resides in the novel features of form, construction, arrangement, and combination of parts hereinafter described and pointed out in the claims.

In the accompanying drawing,— 40 Figure 1 is a broken front elevational view of a traffic-sign or signal embodying our invention, illustrated as in fixed upstanding signalling position at a street crossing or the like;

45 Figure 2 is a fragmentary side elevational view of the signal, showing the panel or body of the signal in normal raised or signalling position in dot-dash lines and in lower position for indicia repair purposes in full lines; 50 and

Figure 3 is a fragmentary enlarged top-plan view of the sign, showing the post and the bracket-catch thereof.

Referring now more in detail and by reference characters to the drawing, which illustrates a preferred embodiment of our invention, the present traffic sign or signal includes a display-panel A comprising preferably a suitably stamped and formed plate of sheet-metal of suitable contour and provided with a plurality of apertures or openings 1 arranged for visually displaying, with the aid of preferably removably inserted reflecting elements or indicia 2, a suitable traffic notice or the like, such, for instance, as shown, 60 the word "Stop".

The elements 2 are insertable from the back of the panel A for neatly and snugly fitting into the apertures 1 and are detachably or removably retained in position in the apertures 70 2 preferably by means of spring-clips 3, which latter and the main body of the indicia elements 2 project rearwardly from the panel A, as best seen in Figure 2, and are suitably protectively enclosed or housed by a casing or 75 shell 4 secured preferably by means of suitable fastening elements or bolts 5 detachably upon the rear face of the panel A. By withdrawing the bolts 5, the casing 4 may be readily detached from the panel A for repair or 80 replacement of the elements 2.

B designates a post comprising in the present instance a preferably tubular member or pipe, of which an end is in practice firmly set or embedded in the ground, a foundation 85 or the like, for supporting the panel A at a suitably elevated or other readily visible position at a street intersection, as may best serve its intended purpose.

The sign in service is subjected to the damaging influences, not only of wind and weather, but often to accidental or malicious assaults on the part of motorists, pedestrians, and the like. The panel A must hence be firmly and securely attached to the post B and the latter, in turn, firmly and securely set in the ground or other post supporting means, suitably for withstanding the assaults made upon it. At the same time, the rear face of the panel A should be freely accessible for the 100

purpose of renewing or replacing broken or damaged reflecting elements or indicia 2, for maintaining the traffic-warning efficacy of the sign.

- 8 For such several purposes we provide on post B an integral upwardly projecting preferably flattened stem 6 spanning substantially the height or vertical width of the panel A, and at the base of the stem 6 is mounted an 10 angular bracket 7 carrying at its horizontally projecting end a pintle or pin 8, which pivotally supports a co-operating hinge-leaf 9.

The panel A at its lower margin is, by means of suitable fastening elements 10, fixed 15 to the hinge-leaf 9 for swingable movement of the panel A towards and from the stem 6 of the post B.

When the panel A is swung to normal vertical or display-position, as shown in dot-dash lines in Figure 2, the casing 4 will reside so closely adjacent to the post B as to substantially preclude the removal of the casing 4 from the panel A. However, when the panel A is swung downwardly, a projecting margin-25 al portion 11 of the panel A is adapted for engagement from beneath with the bracket 7 for co-operatively therewith supporting the panel A in reclining substantially horizontal non-displaying position on the post, as best seen in full lines in Figure 2, and it will be readily seen that, when the panel A is in such horizontally reclined and supported position, convenient access may be obtained from in front of the sign-structure for removing the 30 casing 4 from the panel A for then most conveniently exposing the indicia 2 and clips 3, and enabling the performance of the necessary servicing or repair work with the greatest ease and dispatch.

40 For securing the panel A in a vertical or indicia displaying position on the fixed post B, we preferably provide a latch-bracket 12 having at an end an angularly depending ear suitably, as at 13, pivotally connected to the 45 panel A adjacent its upper margin. At its other end, the bracket 12 is provided with an angularly upstanding ear or catch 14 adapted for flatwise engagement with the stem 6, the ear 14 being provided with a lateral slot 50 15 having on each of its opposite side margins, at the edge of the ear 14, a projecting lug 16, best seen in Figure 3.

On pivotal actuation of the bracket 12 from reclined position, as shown by dot-dash lines 55 in Figure 1, to vertical position, as shown by full lines in Figure 1, the slot 15 is adapted to embrace a bolt 17 loosely mounted in and through the post stem 6, the bolt 17 having a preferably square-head 18 disposed on the 60 front side of the stem 6 and a nut 19 on the rear side of the stem 6 for drawing the bolt thereon.

Obviously, by slackening off the nut 19, the bolt 17 may be forwardly shifted until its 65 head 18 clears the lugs 16, when the bracket-

latch 12 may be swung as described for engaging the bolt 17. The bolt 17 is then rearwardly shifted for engaging a flat side of the head 18 with the lugs 16, whereby the bolt 17 is held from turning while the nut 19 is tightened, and at the same time the bracket 12 is fastened securely on the bolt 17, as well as to the stem 6.

The panel A, thus retained at both its upper and lower margins securely upon the post B, is fully enabled to safely withstand the stresses to which in service it may reasonably be expected to encounter. At the same time, the panel A may, as we have described, be conveniently manipulated, without disturbing the fixed location of the post B, for repairing or replacing the reflecting elements 2 for completely maintaining the full signalling efficiency of the sign.

It will be understood that changes and modifications in the form, construction, arrangement, and combination of the several parts of our new signal may be made and substituted for those herein shown and described without departing from the nature and principle of our invention.

Having thus described our invention, what we claim and desire to secure by Letters Patent is—

1. In a traffic-sign or the like, a post for embedment in upstanding position in the ground, a panel, an indicia-housing-shell removably disposed on a face of the panel, the panel being hingedly connected at a margin to the post for swingable movement for disposing the shell intermediate the post and the panel when the panel is in indicia-displaying position and for disposing the shell for removal when the panel is in lowered position, and means for releasably securing the panel at another margin to the post in displaying-position, said means including a fastening element on the post, a latch member pivoted on the panel and having a notch for reception of the fastening element, and lugs on the latch member adjacent said notch for retaining the fastening element therein.

2. In a traffic-sign or the like, in combination, a standard, a sign-panel, a housing-shell mounted for removal on the rear face of the panel, and means for hingedly connecting the panel to the standard for swingable movement for non-removably disposing the shell intermediate the standard and the panel when the panel is in display position and for accessibly disposing the shell for removal when the panel is in non-displaying position.

3. In a traffic-sign or the like, in combination, a standard for embedment in upstanding position in the ground, an apertured panel, a signalling-element insertable in said aperture for visible exposure on the outer face of the panel, and a shell mounted for removal in element-housing position on the rear face of the panel, the panel being hing-

edly-connected to the standard for swingable movement for non-removably disposing said shell intermediate the standard and the panel when the panel is in display position and for 5 accessibly disposing the shell for removal when the panel is in non-displaying position.

4. In a traffic-signal or the like, in combination, a standard for embedment in upstanding position in the ground, an apertured 10 panel, a signalling-element insertable in said aperture for visible exposure on the outer face of the panel, a shell mounted for removal on the rear face of the panel for housing said element, and a hinge-bracket having members 15 fixed to the standard and to the panel for connecting the panel to the standard for swingable movement for non-removably disposing said shell intermediate the standard and the panel when the panel is in display 20 position and for accessibly disposing the shell for removal when the panel is in non- display position.

5. In a traffic-signal or the like, in combination, a standard for embedment in upstanding 25 position in the ground, an apertured panel, a signalling-element insertable in said aperture for visible exposure on the outer face of the panel, a shell mounted for removal on the rear face of the panel for housing said 30 element, a hinge-bracket having a first member fixed to the standard and a second member fixed to a margin of the panel for connecting the panel to the standard for swingable movement for non-removably disposing 35 said shell intermediate the standard and the panel when the panel is in display position and for accessibly disposing the shell for removal when the panel is in non-display position, and means for releasably securing the 40 panel at another margin to the standard in displaying-position.

6. In a traffic-signal or the like, in combination, a standard for embedment in upstanding 45 position in the ground, an apertured panel, a signalling-element insertable in said aperture for visible exposure on the outer face of the panel, a shell mounted for removal on the rear face of the panel for housing said element, a hinge-bracket having a first member 50 fixed to the standard and a second member fixed to a margin of the panel for connecting the panel to the standard for swingable movement for non-removably disposing said shell intermediate the standard and the 55 panel when the panel is in display position and for accessibly disposing the shell for removal when the panel is in non-display position, and means including a fastening element on the post and a member pivotally mounted 60 on the panel co-operable with the fastening element for releasably securing the panel at another margin to the post in displaying- position.

7. In a traffic-signal or the like, in combination, a standard for embedment in upstand-

ing position in the ground, an apertured panel, a signalling-element insertable in said aperture for visible exposure on the outer face of the panel, a shell mounted for removal on the rear face of the panel for housing said element, and means including a hinge-bracket 70 having co-operably jointed members fixed to the standard and the panel for connecting the panel to the standard for supporting the panel in upright position approximately parallel with the standard with the shell non-removably disposed intermediate the standard and the panel and for also supporting the panel in reclining approximately horizontal position relatively to the standard for accessibly presenting the shell for removal.

In testimony whereof, we have signed our names to this specification.
